US00D901805S

(12) **United States Design Patent** (10) Patent No.: **US D901,805 S**
 Keith et al. (45) Date of Patent: ** Nov. 10, 2020

(54) **CLEANING ARTICLE**

- (71) Applicant: **The Procter & Gamble Company**, Cincinnati, OH (US)
- (72) Inventors: **Brian Lee Keith**, Hammersville, OH (US); **Nicola John Policicchio**, Mason, OH (US)
- (73) Assignee: **The Procter & Gamble Company**, Cincinnati, OH (US)
- (**) Term: **15 Years**
- (21) Appl. No.: **29/679,671**
- (22) Filed: **Feb. 8, 2019**

Related U.S. Application Data

- (62) Division of application No. 29/607,995, filed on Jun. 19, 2017, now Pat. No. Des. 846,213.

Primary Examiner — John R Yeh*(74) Attorney, Agent, or Firm* — John T. Dipre(57) **CLAIM**

The ornamental design for a cleaning article, as shown and described.

DESCRIPTION

FIG. 1 is a perspective view of a cleaning article;
 FIG. 2 is a bottom plan view thereof; and,
 FIG. 3 is a top plan view thereof.

The broken lines in the figures illustrate portions of the cleaning article that form no part of the claimed design.

1 Claim, 3 Drawing Sheets(56)
